UNITED STATES PATENT OFFICE

115,701

DESIGN FOR A BEDSPRING

Edward L. Bronstien, St. Paul, Minn.

Application February 29, 1936, Serial No. 61,428

Term of patent 14 years

To all whom it may concern:

Be it known that I, Edward L. Bronstien, a citizen of the United States, residing in the city of St. Paul, county of Ramsey, and State of Minnesota, have invented a new, original, and ornamental Design for a Bedspring, of which the following is a specification, reference being had to the accompanying drawings, forming a part thereof.

Figure 1 of the accompanying drawings is a top plan view of a one-quarter section of a bedspring

showing my new design, the remaining three-quarters of the bedspring being repetitious of what is shown, and

Figure 2 is a perspective view on a larger scale showing my design on a corner portion of the bedspring.

I claim:

The ornamental design for a bedspring, as shown and described.

EDWARD L. BRONSTIEN.
